UNITED STATES PATENT OFFICE.

WILLIAM LYON, OF NEWARK, NEW JERSEY.

BOOT OR SHOE.

SPECIFICATION forming part of Letters Patent No. 269,077, dated December 12, 1882.

Application filed October 6, 1882. (No model.)

To all whom it may concern:

Be it known that I, WILLIAM LYON, of Newark, in the county of Essex and State of New Jersey, have invented certain new and useful 5 Improvements in Boots or Shoes; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal sectional view of a boot or shoe constructed with my improvements. Fig. 2 is a cross-section of the same, 15 and Figs. 3 and 4 are plan views of the inner and outer metallic soles.

Similar letters of reference indicate corresponding parts in all the figures.

20 My invention relates to improvements in boots or shoes; and it consists in the improved construction of the same, as hereinafter more fully described and claimed.

In the accompanying drawings, the letter A 25 represents the outer sole of a boot or shoe, and B the insole. Between these two soles are interposed, in place of the usual co-called "bottom-filling" or interposed sole of inferior leather, two soles of zinc or other soft metal, 30 C and D, with a thin leather or skin sole, E, between them. These three soles are smaller than the outer sole and are surrounded by the welt. The inner metallic sole, C, and the thin leather sole E are cut of the same shape as 35 the space inside the welt, while the outer metallic sole, D, is provided with two projecting lips, d and d', at the heel and toe, which are bent over the soles C and E and clasp them. The edges D' of the shank of sole D are beaded 40 over two pieces of steel wire, F, which serve to strengthen the shank and retain its shape.

It will be seen that by using these metallic soles between the inner and the outer sole of a boot or shoe the sole will be strengthened

for wear, as, if the outer sole is worn through, 45 the metallic sole will offer more resistance than the leather filling, which, especially in the cheaper grades of boots or shoes, generally is composed of scraps and pieces of leather cemented together.

By having the two metallic soles with interposed leather or skin sole the boot or shoe is made warmer, as an air-space is formed between the two metallic soles, as well as making the boot or shoe stronger, and preventing 55 the shoe from squeaking by having the soft metal interposed between each layer of leather, as the friction of the leather upon the soft metal produces no sound. The interposed filling of leather or skin may also be composed 60 of scraps or smaller pieces of leather, as it will not be subjected to wear, and will be held together by the two inclosing metallic soles, thus enabling the manufacturer to use even the smallest scraps to advantage.

Having thus described my invention, I claim and desire to secure by Letters Patent of the United States—

1. A boot or shoe having two metallic soles with a thin leather sole interposed, and all 70 three layers placed between the inner and outer soles of the shoe or boot, substantially as and for the purpose herein shown and set forth.

2. In a shoe or boot, the metallic sole D, 75 having lips d and d', adapted to clasp the inner metallic sole, C, and intermediate leather sole, E, and having the edges D' of the shank beaded over steel wires F, substantially as and for the purpose herein shown and set forth. 80

In testimony that I claim the foregoing as my own I have hereunto affixed my signature in presence of two witnesses.

WILLIAM LYON.
